HAND SWIMMING FLIPPER

Raoul L. Lassonde, 2610 Girouard Blvd.,
St. Hyacinthe, Quebec, Canada

Filed July 24, 1961, Ser. No. 66,020

Term of patent 14 years

(Cl. D71—1)

FIG. 1

FIG. 2

FIG. 3

FIG. 4

FIGURE 1 is a perspective view of the top side of a hand swimming flipper showing my new design.

FIGURE 2 is a bottom plan view thereof.

FIGURES 3 and 4 are sectional views thereof taken on the lines 3—3 and 4—4 of FIGURE 2, respectively.

The strap is broken away in FIGURE 3 for convenience of illustration.

I claim:

The ornamental design for a hand swimming flipper, as shown and described.
